US00D924030S

(12) **United States Design Patent** (10) Patent No.: **US D924,030 S**
Kaye, Jr. et al. (45) Date of Patent: ** Jul. 6, 2021

(54) **BLADE FOR OSCILLATING POWER TOOLS**(71) Applicant: **BLACK & DECKER INC.**, New Britain, CT (US)(72) Inventors: **Thomas R. Kaye, Jr.**, Fallston, MD (US); **Bradley J. Nohr**, Bel Air, MD (US)(73) Assignee: **Black & Decker Inc.**, New Britain, CT (US)(**) Term: **15 Years**(21) Appl. No.: **29/709,971**(22) Filed: **Oct. 18, 2019****Related U.S. Application Data**

(63) Continuation of application No. 29/639,883, filed on Mar. 9, 2018, now Pat. No. Des. 871,185, which is a continuation of application No. 29/591,013, filed on Jan. 16, 2017, now Pat. No. Des. 814,900.

CLAIM

The ornamental design for a blade for oscillating power tools, as shown and described.

DESCRIPTION

FIG. 1 is a top perspective view of a blade for oscillating power tools in accordance with a first embodiment.

FIG. 2 is a right side elevation view thereof;

FIG. 3 is a left side elevation view thereof;

FIG. 4 is a rear elevation view thereof;

FIG. 5 is a front elevation view thereof;

FIG. 6 is a top plan view thereof;

FIG. 7 is a bottom plan view thereof; and

FIG. 8 is a bottom perspective view thereof.

FIG. 9 is a top perspective view of a blade for oscillating power tools in accordance with a second embodiment.

FIG. 10 is a right side elevation view thereof;

FIG. 11 is a left side elevation view thereof;

FIG. 12 is a rear elevation view thereof;

FIG. 13 is a front elevation view thereof;

FIG. 14 is a top plan view thereof;

FIG. 15 is a bottom plan view thereof; and

FIG. 16 is a bottom perspective view thereof.

FIG. 17 is a top perspective view of a blade for oscillating power tools in accordance with a third embodiment.

FIG. 18 is a right side elevation view thereof;

FIG. 19 is a left side elevation view thereof;

FIG. 20 is a rear elevation view thereof;

FIG. 21 is a front elevation view thereof;
FIG. 22 is a top plan view thereof;
FIG. 23 is a bottom plan view thereof; and
FIG. 24 is a bottom perspective view thereof.
FIG. 25 is a top perspective view of a blade for oscillating power tools in accordance with a fourth embodiment.
FIG. 26 is a right side elevation view thereof;
FIG. 27 is a left side elevation view thereof;
FIG. 28 is a rear elevation view thereof;
FIG. 29 is a front elevation view thereof;
FIG. 30 is a top plan view thereof;
FIG. 31 is a bottom plan view thereof; and
FIG. 32 is a bottom perspective view thereof.
FIG. 33 is a top perspective view of a blade for oscillating power tools in accordance with a fifth embodiment.
FIG. 34 is a right side elevation view thereof;
FIG. 35 is a left side elevation view thereof;
FIG. 36 is a rear elevation view thereof;
FIG. 37 is a front elevation view thereof;
FIG. 38 is a top plan view thereof;
FIG. 39 is a bottom plan view thereof; and
FIG. 40 is a bottom perspective view thereof.
FIG. 41 is a top perspective view of a blade for oscillating power tools in accordance with a sixth embodiment.
FIG. 42 is a right side elevation view thereof;
FIG. 43 is a left side elevation view thereof;
FIG. 44 is a rear elevation view thereof;

FIG. 45 is a front elevation view thereof;
FIG. 46 is a top plan view thereof;
FIG. 47 is a bottom plan view thereof; and
FIG. 48 is a bottom perspective view thereof.
FIG. 49 is a top perspective view of a blade for oscillating power tools in accordance with a seventh embodiment.
FIG. 50 is a right side elevation view thereof;
FIG. 51 is a left side elevation view thereof;
FIG. 52 is a rear elevation view thereof;
FIG. 53 is a front elevation view thereof;
FIG. 54 is a top plan view thereof;
FIG. 55 is a bottom plan view thereof; and
FIG. 56 is a bottom perspective view thereof.
FIG. 57 is a top perspective view of a blade for oscillating power tools in accordance with an eighth embodiment.
FIG. 58 is a right side elevation view thereof;
FIG. 59 is a left side elevation view thereof;
FIG. 60 is a rear elevation view thereof;
FIG. 61 is a front elevation view thereof;
FIG. 62 is a top plan view thereof;
FIG. 63 is a bottom plan view thereof; and
FIG. 64 is a bottom perspective view thereof.
The broken lines in the drawings illustrate portions of the blade for oscillating power tools that form no part of the claimed design.
